UNITED STATES PATENT OFFICE.

JAMES H. DYETT, OF BUFFALO, NEW YORK.

DESIGN FOR A CONNECTING-PIECE FOR BEDSTEADS.

SPECIFICATION forming part of Design No. 35,869, dated April 15, 1902.

Application filed February 17, 1902. Serial No. 94,500. Term of patent 3½ years.

To all whom it may concern:

Be it known that I, JAMES H. DYETT, a citizen of the United States, residing at Buffalo, in the county of Erie and State of New York, 5 have invented and produced a new and original Design for a Connecting-Piece for Bedsteads, of which the following is a specification, reference being had to the accompanying drawings, making a part hereof.

10 My invention relates to the shape or configuration of the connecting-pieces used in connecting the vertical upright rods with the horizontal cross-rods in the footboards and headboards of bedsteads and cots.

15 In the accompanying drawings, Figure 1 is a front elevation of a connecting-piece embodying my design. Fig. 2 is a side elevation of the same. Fig. 3 is a plan of the same as it appears from below.

As shown in the drawings, the leading or 20 characteristic feature of my design consists of the ornamental top A, in the form of a conventionalized flower, with three leaves or petals, the central one of which leaves is substantially upright, with the other two leaves 25 somewhat drooping, one on each side of the central leaf, as shown in the drawings, upon the stem B, the hollow transverse cylinder C at the bottom of the stem B, and the stem or cylinder D, intersecting the cylinder C, as 30 shown.

What I claim is—

The design for a connecting-piece for bedsteads substantially as shown and described.

JAMES H. DYETT.
